CAN BODY MAKING MACHINE

Axel Johnson, deceased, late of Oakland, Calif., by
 George Walter Johnson and Lloyd A. Johnson,
 executors, Oakland, Calif., and George Walter
 Johnson, Oakland, Calif.

Application May 4, 1936, Serial No. 77,744

15 Claims. (Cl. 113—10)

The present invention relates to can body manufacturing machinery, and more particularly to the roll type machine in which cylindrical can bodies are formed upon a cylindrical horn.

Attempts to speed up production by machines of this type have led to the development of body forming machines capable of producing in the neighborhood of three hundred cans a minute from a single horn by feeding preformed blanks thereto, and other expedients; at such speeds, however, that jamming of the machine may occur from many causes and is much more serious than in a machine operating more slowly.

The machine of the present invention, by providing a plurality of horns upon which the several forming operations are performed, makes possible a lower machine speed with a corresponding freedom from liability to jam, and also makes possible the economical use of ordinary sheet material which is formed into can blanks prior to being fed to the horn mechanism. Furthermore, the output of the two forming horns may be passed over a single soldering bath which need be but little wider than the bath required for a soldering roll serving a single line of cans, and need not be as long due to the decreased speed of operation of the machine. Thus the cost of heating the solder bath and the solder losses through oxidation, are substantially less than they would be for two machines of equal output capacity.

A principal object of the invention is the provision of a machine in which blanks prepared by the machine may be separately passed through concurrently operating forming devices in parallel lines to a single soldering bath for the final operation.

Another object of the invention is the provision of an improved means for preforming a plurality of can blanks from a single sheet of material.

Another object of the invention is the provision of an improved means for separating blanks preformed from a single sheet of material, and feeding them to the forming devices.

Other objects will appear in the course of the following description of a specific embodiment of the invention, reference being had to the accompanying drawings, in which:

50 Figure 1 is a plan view of a machine embodying the invention.

Figure 2 is a side elevation thereof having a portion of the base structure cut away to show the driving mechanism.

55 Figure 3 is a section on line 3—3 of Figure 1,

illustrating the power transmission devices and magazine feeding arrangement.

Figure 4 is a longitudinal sectional view on the line 4—4 of Figure 1, centrally of the machine.

Figure 5 is a longitudinal sectional view on line 5—5 of Figure 1, illustrating the interior of one of the transmission housings of the machine.

Figure 5A is a detailed sectional view of the forming rolls of the machine.

Figure 6 is a lateral sectional view on line 6—6 of Figure 1 through the forming rolls and a portion of the horn section of the machine.

Figures 6A, B, and C are detailed sectional views of a portion of the feeding mechanism of the machine.

Figure 7 is a detailed sectional view of the feed bar operating mechanism taken on the line 7—7 of Figure 1.

Figure 7A is a detailed sectional view of a spring feed pawl.

Figure 7B is a detailed sectional view of a spring finger feed stop.

Figure 8 is a detailed sectional view of the hook forming mechanism taken on the line 8—8 of Figure 1.

Figure 9 is a detailed sectional view of the bumping mechanism taken on the line 9—9 of Figure 1.

Figure 10 is a sectional view illustrating the inverter mechanism and taken on the line 10—10 of Figure 1.

Figure 11 is a detailed view, partially in section, showing details of the bumping mechanism.

Figure 11A is a detailed sectional view through an expanding section of the horn.

Figures 12, 12A, and 12B are detailed views of a portion of the power transmission mechanism.

Figure 13 is a diagrammatic view illustrating the several steps in the formation of can bodies from sheet material.

Figure 14 is a detailed view, partly in section, of the corner clipping mechanism.

Referring to the embodiment of the invention illustrated in the accompanying drawings, and more specifically to Figures 1, 3, and 5 thereof, the various mechanisms hereinafter described are supported upon a base 21, upon which are mounted at opposite sides transmission housings 23. Power is supplied to the various mechanisms of the machine by a motor 25 enclosed within the base 21 and connected by means of belting 27 with a clutch 29 which may be controlled by means of handle 31 to connect the motor to shaft 33 journaled in brackets 35 depending from the frame 21. An inverted tooth chain 37 (Figures 5

55

and 6) connects a gear 39 fixed on shaft 33 with a gear 41 fixed on shaft 43 (see also Figure 4) extending longitudinally of the machine centrally of base member 21, and provided with a plurality 5 of bearings intermediate its length. Also extending longitudinally of the machine, within the transmission housings 23, are control shafts 45 and 47, each of which is journaled in one of the transmission housings 23 and both of which are 10 driven from the central shaft 43. Control shaft 45 is connected therewith, as shown in Figure 3, by intermeshing idler gears 49 and 51, mounted on plate 53 pivotally adjustable about shaft 43 and adapted to be retained in adjusted position 15 by means of bolt 55 engaging bracket 35 through a slot 57 in said plate 53. Gear 49 meshes with a gear 59 fixed on shaft 45, and gear 51 meshes with a gear 52 on shaft 43, so that as shaft 43 is driven in a clockwise direction, gear 59 and shaft 20 45 will be driven in a counter-clockwise direction. Shaft 47 is connected with shaft 43 by means of an idler gear 61 mounted on a plate 63 pivotally adjustable about shaft 43 and adapted 25 to be retained in adjusted position by means of a bolt 65 engaging bracket 35 through a slot 67 in the said plate 63. Gear 61 meshes with gear 52 fixed on shaft 43 and with a gear 69 fixed on shaft 47 so that as shaft 43 rotates in a clockwise direction, gear 69 will also rotate in a clockwise direction. 30

Material feed

Means are provided for successively removing from a magazine, sheets of material of sufficient size to form two finished cans, and to feed these sheets in a successive step-by-step movement to a plurality of stations in each of which certain steps of the can-forming operations are performed. 35

The successive steps of advance of this sheet material in the formation of the finished cans are illustrated diagrammatically in Figure 13, where in station I the sheet material is stacked in the magazine; in station II a single sheet has been fed from the bottom of the stack; in station III 40 the corners have been clipped; in station IV the requisite piercing operation has been performed; in station V the sheet has been separated into two can blanks; in station VI these blanks have been separated and are being fed laterally into station 45 VII where they are rolled into cylindrical form; in station VIII oppositely disposed hooks have been formed on the edges of the blanks; in station IX these hooks have been interengaged and locked to form a seam; in station X the can has 50 been inverted to place it in proper position for the soldering operation; and, in station XI, solder is being applied to the seam by means of the indicated soldering rolls. 55

As best shown in Figure 3, the magazine 81 is supported at opposite ends upon transmission housings 23 and is provided with beveled side rails 83 cooperating with a rounded center support 85 to hold a stack of metal sheets. Reciprocable vacuum cups 87 are provided, and are adapted to adhere to and deform the lowermost sheet in the magazine so that its leading edge will be carried below gate members 89 projecting downwardly from the front of magazine 81, and to bring the trailing edge of the sheet into the path of the lateral feeding means hereinafter described. 60

Vacuum cups 87 are mounted at opposite ends of a yoke 91 fixed to a vertically reciprocable slide 93 movable in channeled guides 95 on central supporting member 97 by means of pitman 99 con-

nected a pin on said slide with an eccentric 101 fixed to shaft 43 (see also Figure 4). Vacuum cups 87 are periodically evacuated by means of a pump 103 (Figure 4) driven by a crank connection with shaft 43 and connected to the vacuum cups 87 by means of flexible tubing 105. The relative timing is such that the cups are evacuated just prior to the beginning of and during their downward movement. 10

By this operation the lowermost sheet in the magazine is brought into the path of the horizontal feeding mechanism which comprises (as shown in Figure 7A) a series of properly spaced pawls 107 pivotally mounted in bars 109 and pressed upwardly by means of springs 111, each pawl being shouldered as at 112 so that the forward end thereof underlies a complementary shoulder 114 on the rear edge of the next forward bar 109. Pusher pawls of this type are used for advancing the sheet material between the several stations above described, and will be hereinafter referred to in connection with the detailed description of the said stations. 15 20 25

The pusher pawls 107 used for feeding sheet material from the magazine are, as shown in Figures 7 and 7A, mounted on horizontally reciprocable bars 115 to which bars 109 are fixed, and of which, as shown in Figure 3, four are provided across the width of the machine. 30

The pair of bars 115 at each side of the center line of the machine, is connected together by a cross-bar 117 (Figure 7) and each pair may thus be driven by a sinusoidal cam 119 (see also Figure 5) through lever 121 pivoted to links 122 pivoted to the frame at 123, and connected at its upper end by pin 125 with a strap member 127 to which bar 115 is fixed. Roller 129 mounted on lever 121 rides in the groove 131 of cam 119 which is so proportioned as to effect one complete reciprocation of lever 121 for each revolution of the shaft 40 45 upon which the cam 119 is fixed. A similar cam and lever assembly operated by shaft 47 is used to effect identical reciprocation of the two bars 115 on the opposite side of the center line of the machine. 45

In feeding the sheet material it is also desirable to insure that retrograde movement of the material in the direction of feed will not take place, and for this purpose a second set of pawls 107 50 55 above described, is used, but these pawls are not reciprocable, the bars 109a in which they are pivoted being fixed in a frame member of the machine. These pawls are therefore depressed as the sheet material passes over them, but are spring-pressed to raised position after it has passed, to prevent retrograde movement thereof. 60

As the sheet material passes out of the magazine, it moves on to the flat surface 135 (Figures 1, 4, 5, 7, and 14) where it is frictionally retained 60 by means of grills 137 (Figures 1 and 14) comprising a series of bars secured together and adapted to serve as a weight to prevent displacement of the sheet material, being itself secured against displacement by any suitable means. 65 Mounted upon the bars of the grill 137 which extend longitudinally of the machine, are spring stops which, as shown in Figure 7B, each comprise a pivoted finger 139 extending slightly below the lower surface of the bars of grill 137, and 70 normally maintained in vertical position by means of spring 141 seated in block 143 and compressed between a set screw 145 in said block, and a plunger 147, the opposite end of which presses against the upper end of the finger 139. 75

A second set screw 149 is provided for the purpose of permitting adjustment of the finger 139. Spring fingers 139 are so located that the sheet material will be brought against a pair of them at the end of each of the successive feeding steps hereinbefore mentioned, and they thus serve to prevent an overthrowing of the material by momentum and press it back against stops 107a. However, when the pusher pawls 107 again engage the sheet material for the purpose of carrying it forward another step, fingers 139 yield, compressing springs 141 and permitting the material to pass freely under the positive drive of fingers 107.

By this means the sheet material is fed by successive steps from station I (Figure 13) to station VI, the corner clipping, piercing, and shearing operations being performed at the several stations as will be hereinafter described in detail. At station VI the sheared sections of the sheet are moved laterally in opposite directions into the rolling mechanism by mechanism illustrated in Figures 6, 6A and 6B.

Referring particularly to Figure 6B, as the two sections of the sheet pass from station V where the shearing has been effected to station VI, they are separated a short distance vertically by causing one of the sections to pass up a low ramp 151. This vertical separation is just sufficient to permit one of the sheets X (Figure 6A) to pass into the notch 153 of a feed finger 155, while the other sheet Y passes under the offset upper end of said pawl 155, and into the path of movement of a second feed finger 157. These feed fingers 155 and 157 are then moved in opposite directions, separating the sheared sections of the original sheet and moving them laterally in opposite directions to their respective rolling mechanisms, as indicated in Figure 6B.

Feed finger 155 is mounted upon block 159 channeled for tongue and groove engagement as at 161 with a frame member to permit lateral sliding of the said block, and is recessed as at 163 (Figure 6) to receive the upper end of a lever 165 pivoted to the frame at 167 and provided at its lower end with a roller 169 cooperating with cam 171 fixed on shaft 43 so that upon rotation of the said shaft the feed finger 155 will be reciprocated to feed the sheet in engagement therewith laterally of the machine. Feed finger 157 is similarly mounted on a similar block 173, the recessed under side of which is engaged by a lever 175 also pivoted to the frame at 167 and provided at its lower end with a roller 177 cooperating with a similar cam 179 fixed on shaft 43 so that upon rotation of the said shaft the feed finger 157 will be reciprocated in the opposite direction to feed its sheet laterally of the machine. Spring 181, tensioned between a stud on lever 165 and a stud on lever 175, tends to maintain the feed fingers 155 and 157 in the position in which they are shown in Figure 6A.

By means of these feed fingers 155 and 157 the two blanks are fed laterally, passing through rolls 261 and 263 and past the bending member 291 by which it is bent into the open-edged cylindrical form around the horn 281, indicated at station VII in Figure 13. The construction and operation of the roll mechanism and horn will be hereinafter described in detail, the present description being concerned specifically with the blank feeding devices.

From station VII the blank is fed by successive steps to station X, indicated in Figure 13, by mechanism illustrated in Figures 6, 7, 7A, 8, 9,

and 11A, comprising feed bars 185 and 187 corresponding in construction to the feed bars 115 (Figure 7A) and each provided with spring pusher fingers or pawls 107 corresponding to those described in detail in connection with the previous description of the structure shown in Figure 7A.

Reciprocation of the feed bars 185 and 187, for the purpose of feeding the partially formed can along the horn is effected, as shown in Figure 7, by means of the strap member 127 which is curved to extend partially around the horn and connected with the feed bars 185 and 187 by pin 125, pin 126, and screw 189, respectively. By this means, bars 185 and 187 are reciprocated longitudinally of the machine in synchronism with the reciprocation of feed bars 109 previously described in connection with the earlier description of the mechanism shown in Figure 7.

When the material has reached station X (Figure 13), all forming operations thereon have been completed, as will appear from the following description, and the formed can body is removed from the horn by mechanism which will be hereinafter described in detail.

25

Corner clipping mechanism

As the blanks are fed from the magazine to the several successive stations hereinbefore described, they are successively brought into cooperative relationship with mechanism for clipping the corners from the sheets, for piercing the sheets to provide ears adjacent the unclipped corners, for shearing the sheet to separate it into two can blanks, for forming each of these two blanks into open-edged cylindrical bodies; for then forming oppositely disposed hooks on the adjacent edges of these bodies, then for interengaging the hooks and bumping the interengaged hooks to form a side seam, closing the cylinder. The mechanism for performing these several operations will now be described in detail.

For clipping the corners of the sheet to the form in which it is shown in station III in Figure 13, mechanism is provided as shown in Figures 1, 2, 5, and 14, comprising four cutter discs 201 adjustably fixed on shaft 203 by means of nut 205 (Figure 5) by means of which the discs 201 may be held in operating position against flange 207 integral with the shaft 203 and with its operating lever arm 209 (Figure 14). As shown in Figure 1, contiguous arms 209 are connected together by a pin 211 on which is pivoted a push link 213 (see also Figure 5), operable, in the case of one of the pairs of cutting discs, by an eccentric 215 fixed on shaft 45 and embraced by a strap on the lower end of the link 213, and in the case of the opposite pair of cutting discs, by a similar eccentric mounted on the opposite longitudinal shaft 47.

Each of the shafts 203 is mounted in a separate journal bracket 217 secured to the frame by bolts 219 (Figure 14) passing through loosely fitting holes in the bracket and the frame member so that minor adjustments of the cutting discs 201 may be effected by loosening the bolts and adjusting the journal brackets with respect to the frame member.

By this means all of the cutting discs 201 are periodically given an oscillating movement sufficient to bring their cutting edges 221 (Figure 14) into slots provided in the die block 223 secured to the frame adjacent thereto and to remove the corners from blanks fed successively into cooperative relationship therewith, as shown at station 75

- III (Figure 13). From the corner-clipping station, designated station III in Figure 13, the sheets are successively advanced to station IV where two short longitudinal slits are pierced 5 in the sheet so that after shearing it will present ears adapted to overlap the opposite clipped corners.

Piercing mechanism

- 10 The piercing mechanism, as illustrated in Figures 1 and 4, includes the stationary piercing punches 231 carried by angle brackets fastened to the swingable plate 233 pivotally mounted on shaft 235 and secured to the frame at its opposite end by a bolt and wing nut 237 which may be 15 unfastened to permit the plate 233 to be swung upwardly around shaft 235 in order to permit access to the various mechanisms. Underlying the punches 231 are piercing dies 239 adjustably bolted to plate 241 which is vertically slidably in ways 243 secured to the machine frame. Adjacent its lower edge the plate 241 is pivotally connected by crank pins 245 with pitmans 247 operated by eccentrics 249 fixed to shaft 43, 20 whereby reciprocatory vertical movement is imparted to the plate 241 carrying piercing dies 239 upwardly to effect the piercing of the sheet indicated at station IV in Figure 13.

Shearing operation

- 30 As the sheets are successively advanced to the station designated V in Figure 13, they are sheared into two equal portions, each of which has had all the requisite operations performed upon it to prepare it as a can blank. 35 As shown in Figures 1 and 4, the upper shearing blade 251 is adjustably bolted to the swingable plate 233 which also carries the piercing punches 231, while the lower shearing blade is adjustably bolted to the vertically reciprocable plate 241 40 which also carries the piercing dies 239, as hereinabove described. As the sheets are successively fed to the shearing station designated V in Figure 13, the vertical reciprocation of plate 241 by eccentrics 249 operating through pitmans 247 45 carries the lower shearing blade 273 upwardly, severing the sheet at the shearing station into two separable portions, each of which has clipped corners at one end and ears formed by the piercing and shearing operations at the opposite end. 50 These separate can blanks are then advanced to the next station, VI in Figure 13, where they are separated laterally by the operation of feed fingers 155 and 157 as hereinabove described, and fed to separate sets of forming rolls disposed on opposite sides of the machine.

Forming operation

- 55 The forming mechanism into which the can blanks are fed by feed fingers 155 and 157, are 60 duplicated at each side of the machine, and hence a description of one of them, with reference to Figures 1, 2, 5, 5A, and 6, will serve for both. The movement of the feed fingers 155 and 157 causes the leading edge of each blank to enter 65 between upper and lower forming rollers 261 and 263, respectively (Figure 5A), journaled in bearings 265, and connected together for simultaneous rotation by gears 267, so that both may be driven by motor 269 through chain 271 (Figure 1) 70 extending between motor 269 and a pulley 273 on a shaft extending from the upper roller 261. Brackets 275 retain these rollers against displacement from operating position in one direction while they are urged into intimate frictional contact with the fed can blank by the spring-pressed 75

cradle member 277 underlying the journal bearings 265 of the lower roller 263.

This cradle member 277 is slidably seated in a socket formed in the horn member 281 (Figure 6) which at this station is provided with central recesses underlying the cradle member and adapted to receive springs 283 compressed between said cradle member and set screws 285 which may be adjusted to determine the degree of compression between rollers 261 and 263. 10

At this station the horn member 281 is also recessed to receive the feed bars 185 and 187 the function of which is to feed the formed can blanks parallel to the longitudinal axis of the horn, as heretofore described. The horn is protected by four hardened plates 287 which serve as retainers for the feed bars, and serve to protect the horn member 281 against wear. 15

As the blank passes through between rollers 261 and 263, moving transversely with respect to 20 the longitudinal axis of the horn, its upper surface comes into contact with the edge of a bending member 291 (Figure 6), the edge of which is located slightly below the point of tangency between rollers 261 and 263 so that the blank is bent 25 downwardly into the form of an open-edged cylinder embracing the horn member 281 and lying between the plate 287 and cover members 293.

As each blank is fed into this position the feed bars 185 and 187 are being retracted in preparation for feeding the blank parallel to the longitudinal axis of the horn 281, to the next station. In order, therefore, to eliminate the possibility of the can blank being forced into contact with the side of one of the feed fingers 107 during the 35 aforesaid feeding movement of the blank transversely with respect to the longitudinal axis of the horn, whereby the machine might be jammed, means are provided for retracting the cover plates 293 during this feeding operation and for 40 causing them to move back toward the horn at the conclusion thereof so that the blank after its formation into cylindrical form may be retained in position to be fed parallel to the longitudinal axis of the horn by the feed fingers carried by bars 185 and 187. 45

For this purpose the cover plates 293 are mounted on levers 295 which are made in two sections bolted together at 297 to permit the covers to be manually swung away for access to 50 the horn member, and a third cover plate 294 is mounted on the upper end of lever 296 pivoted at 299. Levers 295 are also pivotally mounted on the frame at 299 and are provided at their lower ends with rollers 301 pressed by springs 303 55 against cams 305 fixed on shaft 45, lever 296 being operated by cam 306 thereon.

By this arrangement springs 303 serve to move cover plates 293 and 294 away from the horn as soon as the highs of cams 305 and 306 pass from 60 under the lever rollers. Immediately thereafter the can blank is fed through rollers 261 and 263 into cylindrical form around the horn 281, and at the conclusion of this operation the cams rock levers 295 and 296 to bring cover plates 293 and 65 294 back into the position in which they are shown adjacent the horn and leaving only sufficient space between them and the surface of the horn to permit free passage of the can blank during its feeding operation by feed bars 185 70 and 187.

Hook-forming mechanism

Upon completion of the first forming operation above described, the can blank is moved by feed 75

bars 185 and 187 along the horn to the next station, designated station VIII in Figure 13, where mechanism is provided for forming oppositely disposed hooks on the free edges of the blank.

At this station, as shown in Figure 8, the top portion of the horn member 281 is cut away, allowing the upper edges of the hardened members 287 to project for a purpose which will appear more fully hereinafter, and there is provided adjacent the under side of the horn member 281 a spring-pressed rail 311 guided between brackets 312 fixed to the frame and pressed by spring 313 against the horn so as to frictionally retain, in operating position, the blank fed to that position for the hook-forming operation.

Cooperating with this holding means are pressure plates 315, mounted on the upper ends of levers 317 which are formed in two parts secured together by bolts 319 which may be loosened to permit the upper ends of the levers to be pivoted away from the horn to permit access thereto. Levers 317 are pivotally mounted on the frame at 321 and are provided at their lower ends with rollers 323, cooperating with a cam mounted on shaft 45 and proportioned to bring the pressure plates 315 firmly against a can blank surrounding the horn in the hook-forming station during the hook-forming operation.

30 The hook-forming mechanism comprises a hook-forming tool 327 fixed on shaft 329 journaled on the machine frame and provided at its opposite end with a lever arm 331 pivotally connected at 333 to operating link 335, the angular lower end of which is adjustably connected by means of nuts 337 with operating bar 339, the lower end of which is pivotally connected at 341 with straps 343 embracing an eccentric 345 fixed on shaft 45. By this arrangement, upon rotation of the shaft 45 the hook-forming tool 327 is given a clockwise movement, bending the projecting edge of the can blank downwardly around the projecting edge of the hardened elements 287 to the form shown in Figure 8.

45 The opposite hook is formed by a hook-forming tool 347 fixed on shaft 349 journaled in the machine frame and provided at its opposite end with a lever 351 pivotally connected at 353 with a link 355, the angular lower end of which is adjustably connected by means of nuts 357 with operating rod 359. The lower end of this rod is fixed by nut 361 threaded thereon to the straps 343 embracing the eccentric 345 mounted on shaft 45. By this arrangement, upon rotation of the shaft 45 the hook-forming tool 347 is given a counterclockwise movement, bending the projecting edge of the can blank upwardly about the edge of the right-hand pressure plate 315 to the form shown in Figure 8.

60 At the completion of this operation, the cam cooperating with pressure plate rollers 323 permits springs 363, compressed between a socket nut mounted on the frame and the lower portions of levers 317 to move the pressure plates 315 away from the horn and permit the feeding bars 185 and 187 to move the can blank to the next station.

Hook-joining and bumping mechanism

70 The mechanism of the hook-joining and bumping stations, designated station IX on Figure 13, is shown in detail in Figures 9, 11, and 11A.

The horn at this section is of smaller diameter than at the preceding stations, so that the hooked edges of the can blank may be interengaged as

hereinafter explained, but it is expandible to permit interengagement of the hooks after the edges of the blank have been overlapped. For this purpose the horn at this station is made in three sections, as shown in detail in Figure 11A.

The central section 282 is recessed to receive fulcrum rods 365 rockably supporting the outer sections of the horn 367 which are provided with complementary recesses adjacent the rod 365. The outer sections 367 are normally held as closely against the inner section 282 as the adjustable set-screws 369 will permit, by springs 371 compressed between seats formed in the sections 367 and the heads of bolts 373 carried by the inner section 282 and projecting into recesses formed in the outer sections 367. Expansion of this horn section is effected by depressing wedge bolts 375, the upper ends of which are accessible through apertures 377 at the upper side of horn member 282 and the lower ends of which are provided with cam faces cooperating with complementary cam faces on laterally movable bolts 379 slidable in a transverse aperture in the inner section 282 to press outwardly against set-screws 369 carried by the outer sections 367 and move such outer sections outwardly compressing springs 371.

As shown in Figure 9, hook-engaging plates 381 and 383 are provided at this station to effect interengagement of the previously formed hooked edges of the can blank. Plate 381 is mounted at the upper end of a lever 385 which is made in two sections secured together by bolt 387 which may be loosened to permit the plate 381 to be pivoted back away from the horn to permit access thereto. The lever 385 is pivoted to the frame at 389 and provided at its lower end with a roller 391 pressed by spring 393, compressed between a socket nut on the frame and the lower portion of the lever 385, against a cam fixed on shaft 45.

35 Plate 383 is similarly mounted on the upper end of an identically formed lever 395 pivoted on the frame at 397 and provided at its lower end with a roller cooperating with a second cam mounted on shaft 45 against which the said roller is pressed by a similar spring arrangement.

40 The timing of the cams operating levers 385 and 395 is such that lever 385 is rocked to bring the plate 381 against the horn before rocking of the lever 395 takes place, thus insuring that the upturned hook will first be placed against the horn and that the downturned hook moved by plate 383 will thereafter be overlapped, thus insuring proper interengagement of the two hooked edges of the blank.

45 Upon interengagement of the hooked sections as above described, the plates 381 and 383 are moved away from the horn and bumping mechanism is then brought into action to expand the horn sections and hammer the interengaged hooks 50 to form a compact seam, forming the blank into a closed cylinder.

55 This bumping mechanism, as shown in Figure 9, comprises a bumping link 401, guided adjacent its upper end by a link 403 pivotally connected to the link and to the machine frame, and supported at its lower end by an eccentric 405 fixed on shaft 45. Carried on the upper end of the bumping link 401 is a hardened bumping member 407 disposed directly over the interengaged hooked edges of 60 the blank and (see also Figures 11 and 11A) a pair of adjustably mounted horn expanders 409 disposed above the horn section beyond the ends of the can blank and directly above the apertures 377 through which they are adapted to enter the 65

- horn and depress the wedge bolts 375 to effect expansion of the horn substantially simultaneously with the bumping action, the adjustment being preferably such that expansion of the horn begins sufficiently before the member 407 passes into contact with the interlocked hooked edges of the blank, to permit it to be completed substantially simultaneously with the bumping action.
- 10 In order to sustain the horn during this bumping action and localize the stresses incident thereto, a supporting member 415 (Figure 9) is mounted on an eccentric fixed to shaft 45 and preferably integral with the eccentric 405 operating the bumper link 401. The upper end of member 415 projects through the housing 23 and, by means of its operating eccentric, is brought into contact with the can blank at the under side of the horn, substantially simultaneously with the descent of the bumping member 407 thereupon. By this means all stresses incident to the bumping operation are directly localized within the double eccentric 405 mounted on shaft 45 which member may be made sufficiently heavy to sustain such stresses without affecting in any way the design of adjacent elements of the machine.
- 30 Feed bars 185 terminate short of the bumping station, but the feed bar 187 extends through this station and functions at the conclusion of the bumping operation to feed the cylindrical can body off the recontracted horn section into the conveying mechanism hereinafter described.

35

Inverter and conveyor

- From the bumping stations at each side of the machine, the cylindrical can bodies are passed into an inverting mechanism provided for the purpose of placing the seams in proper position 40 on the under side of the cylinder for operation of the soldering rolls, and in order to bring the can bodies from the two forming lines onto conveyor lines disposed sufficiently closely together to facilitate the application of solder to the seams 45 of both lines from a single soldering bath.

- The inverter and conveyor mechanism, as disclosed in Figures 1, 2, 10, 12, 12A, and 12B, comprises a pair of spiders 425 (Figure 10), each of which is provided with a plurality of pockets 50 427 sized to receive the can bodies and provided with a series of projections 429 adapted to frictionally engage the can bodies sufficiently closely to prevent their rotation in the pockets.

- The spiders 425 are driven from shaft 43 by 55 means of an intermittent power transmission arrangement designed to move each of the spiders through one-sixth of a rotation during one-half of each rotation of shaft 43 and to maintain the spiders stationary during the remainder of 60 each rotation of shaft 43.

- This is accomplished by means of the gearing disclosed in detail in Figures 12, 12A, and 12B, comprising a driving gear 431 fixed on shaft 43 and cooperating with a driven gear 433 fixed 65 on the cross shaft 435 journaled in the machine frame. Driving gear 431 is provided with teeth of the conventional form over about half of its periphery, but over the remaining half there extends a single tooth 437 adapted to pass through 70 a gap 439 between the conventional teeth of the driven gear 433, so that the driven gear 433 is locked in a definite cyclic position during half of the cycle, after which it is picked up gradually, the rate of acceleration depending upon 75 the radius of curvature R between the straight

portion of tooth 437 and the conventional tooth of which it is an extension. Thereafter the driving and driven gears function in the ordinary manner until the interruption 439 of the teeth of the driven gear 433 again meets the straight 5 extended tooth 437 of the driving gear 431. Spiders 425 are driven from shaft 435 by means of beveled gears 441 in the manner above described. The cylindrically formed can bodies are deposited by the feed bars 187 from the bumping station 10 into spider pockets located at the positions designated "A" and are conveyed thence by successive movements of the spiders to the positions designated "B" where they are removed by chain conveyor mechanism operated by a second set of 15 intermittent gearing identical with that described in connection with the operation of the spiders 425, but timed to drive the chain conveyor mechanism during the portion of the cycle of shaft 43 during which the spiders are stationary, and 20 to maintain the chain conveyor mechanism stationary during the portion of the cycle of shaft 43 during which the spiders are moving.

This chain conveyor mechanism, as shown in Figures 1, 2, and 10, comprises chains 451 passing 25 over sprockets 453 mounted on shaft 455 journaled in a frame bracket and driven by means of intermittently operated gear 457 driven from shaft 43 as above described. At the opposite end thereof chains 451 are supported by sprockets 30 452 mounted on shaft 459 also journaled in the frame brackets, and at intervals along their lengths, they are provided with can pusher members 461 adapted to contact the trailing edges of cans located in the spider pockets at position B 35 and move the said cans out of the spider pockets into passages defined by sets of four rods 465 (Figures 1 and 2), supported by frame brackets 467 or any other suitable means.

As the can bodies reach the end of the intermittently operating chains 451, they are picked up by pushers 471 carried on continuously moving, separately driven chains 472 passing over sprockets 473 located adjacent the ends of the intermittently operating chains 451, and are conveyed thereby into contact with the upper surfaces of soldering rolls 481 driven by an extension of shaft 43 through transmission mechanism 483 by which solder is applied to the formed seam of the can body in the usual manner from soldering bath 485.

By this arrangement a double row of formed and soldered can bodies is delivered by the conveying mechanism beyond the soldering bath 485.

While a particular embodiment of the invention has been described herein, it will be understood that the same is susceptible of many modifications, and it is understood that the invention is not to be taken as limited except as required by the prior art and by the spirit of the appended 60 claims.

What is claimed is:

1. A can body forming machine comprising a magazine for material, means for feeding material from said magazine along a given path, a 65 pair of forming horns situated at opposite sides of the path along which material is advanced by said feeding means, concurrently operable forming rolls operatively associated with each of said horns, and means for diverting portions of said 70 material from said path into each of said rolls.

2. A can body forming machine comprising a magazine for material, means for feeding material from said magazine along a given path, a pair of forming horns situated at opposite sides of 75

- the path along which material is advanced by said feeding means, concurrently operable forming rolls operatively associated with each of said horns, means for diverting portions of said material from said path into each of said rolls, forming and seaming devices operatively associated with each of said horns, and means for delivering formed can bodies from said horns over a common solder bath.
10. 3. A can body forming machine comprising a magazine for material, means for feeding material from said magazine along a given path, a pair of forming horns situated at opposite sides of the path along which material is advanced by said feeding means, concurrently operable forming rolls operatively associated with each of said horns, means for diverting portions of said material from said path into each of said rolls, forming and seaming devices operatively associated with each of said horns, and means adjacent the discharge end of said horns for inverting formed can bodies and conveying the same over a common solder bath.
15. 4. A can body forming machine comprising a magazine for sheet material, means for feeding sheets successively from said magazine, means for dividing into a plurality of can blanks sheets fed from said magazine, a plurality of concurrently operating horn assemblies including forming and seaming means for forming said blanks into can bodies, means for conveying said blanks from said dividing means into said forming means, and means for discharging the formed can bodies from said horn assemblies over a common solder bath.
20. 5. A can body forming machine comprising a plurality of forming horns, means for receiving sheets of can material adjacent said horns, and sequentially operating devices for first dividing each of said sheets and then feeding a portion of each sheet to a different one of said horns.
25. 6. A can body forming machine comprising a plurality of forming horns, means for receiving sheets of can material adjacent said horns, and sequentially operating devices for first dividing each of said sheets into a plurality of can blanks, and then moving one of said blanks in a direction substantially normal to the plane thereof, and means for engaging the adjacent offset edges of said divisions to feed each to a different one of said horns.
30. 7. A can body forming machine comprising a plurality of forming horns, means for receiving sheets of can material adjacent said horns, and sequentially operating devices for first dividing each of said sheets and then feeding a portion of each sheet to a different one of said horns, forming and seaming devices operatively associated with each of said horns, and means for discharging formed can bodies from said horns over a plurality of soldering rolls operating in a common solder bath.
35. 8. In a machine of the class described, means for feeding sheets of material successively to a series of stations, means at one of said stations for piercing each of said sheets to partially define can blank ears, and subsequently operating means for dividing said sheets into a plurality of blanks, along a line intersecting said piercing at an angle sufficient to complete the definition of said ears.
40. 9. In a machine of the class described, means for feeding sheets of material successively to a series of stations, means at each of said stations for partially defining can blank ears, and subsequently operating means for dividing said sheets into a plurality of blanks, along a line intersecting said piercing at an angle sufficient to complete the definition of said ears.
45. 10. In a machine of the class described, means for receiving and advancing sheets of material, means for dividing said sheets into a plurality of portions, and means for separating said portions comprising means for moving one of said portions in a direction substantially normal to the plane thereof, and means for engaging the adjacent offset edges of the portions to feed each in a different direction.
50. 11. In a machine of the class described, means for receiving and advancing sheets of material, means for dividing said sheets into a plurality of portions, and means for separating said portions comprising means for moving one of said portions perpendicularly with respect to the other, and means for engaging the adjacent offset edges of the portions to feed each in a different direction.
55. 12. In a machine of the class described, means for receiving and advancing sheets of material, means for dividing said sheets into a plurality of portions, and means for separating said portions comprising means for moving one of said portions along an inclined plane to offset the adjacent edges of the portions, and means for engaging said edges to feed each portion in a different direction.
60. 13. In a can body forming machine, forming devices comprising a cylindrical horn, a plurality of movable guide plates partially enclosing said horn, means comprising rollers for bending a sheet to substantially cylindrical form for effecting insertion of sheet material between said horn and said plates, and means operating concurrently with said first means for moving said plates away from said horn while material is being inserted between said horn and said plates.
65. 14. In a can body forming machine, forming devices comprising a cylindrical horn, a set of material feeding devices carried thereby, a plurality of movable guide plates enclosing said horn adjacent said feeding devices, a second set of devices for inserting sheet material between said horn and said plates and bending the same to substantially cylindrical form, and means operating concurrently with said inserting devices for moving said plates away from said horn during the insertion of material by said second set of devices, and to a position adjacent said horn during the feeding of material by said first mentioned devices.
70. 15. In a can body forming machine comprising a plurality of forming horns, each having forming rolls adjacent its upper side and seaming devices operatively associated therewith; the combination of a single solder bath, means for conveying can bodies from said horns over said bath, and means adjacent the discharge ends of said horns for inverting can bodies and transferring them to said conveying means.
